UNITED STATES PATENT OFFICE.

HARRY M. SALYER, OF NEW YORK, N. Y., ASSIGNOR TO THE FIRM OF
LUDWIG AND COMPANY, OF NEW YORK, N. Y.

PLAYING ATTACHMENT FOR MUSICAL INSTRUMENTS.

SPECIFICATION forming part of Letters Patent No. 700,830, dated May 27, 1902.

Application filed June 17, 1901. Serial No. 64,868. (No model.)

To all whom it may concern:

Be it known that I, HARRY M. SALYER, a citizen of the United States, and a resident of the city of New York, in the county of New York and State of New York, have invented certain new and useful Improvements in Playing Attachments for Musical Instruments, of which the following is a specification.

This invention relates to improvements in automatic playing attachments for musical instruments, especially key instruments and the like; and the object of my invention is to provide a new and improved attachment of this kind which is simple in construction, not apt to get out of order, and is reliable in action.

In the accompanying drawings, in which like letters of reference indicate like parts in all the figures, Figure 1 is an elevation of my attachment as applied on a keyboard, parts being broken away, some in section, and some omitted. Fig. 2 is an enlarged detail vertical sectional view of one of the key-strikers and the pneumatic mechanism for actuating the same. Fig. 3 is an enlarged detail vertical sectional view of one of the compressed-air-controlling valves. Fig. 4 is a plan view of the reversing-gear and parts thereof. Fig. 5 is a transverse vertical sectional view through the tracker-board or bridge.

The piston-rod A is guided in the neck A' of a funnel-shaped body A², on the edges of which the edge of a diaphragm A³ is clamped by a cap A⁴, suitably secured in the open end of the funnel A². The diaphragm A³ rests on a head A⁵ on the inner end of the rod A and is pressed inward by a helical spring A⁶, surrounding the rod A, as shown in Fig. 2. A block B is formed on the cap A⁴ and is provided with a bore B', terminating in the chambers B² and B³, and from said bore B' a duct B⁴ leads to the top of the cap A⁴. A valve-stem C is mounted loosely in the bore B' and carries at opposite ends the two valves C' and C², which can seat on valve-seats formed at the ends of the bore B'. The chamber B² is closed by a diaphragm C³, held by a cap C⁴ in an enlargement C⁵ of the block B, and the end of the valve-stem C rests against one face of the diaphragm C³. On the other face of

the diaphragm C³ a helical spring C⁶ rests, which is interposed between the diaphragm C³ and the cap C⁴. The cap C⁴ has a neck C⁷, from which a tube D extends to a tracker-board E.

C⁸ is a vent-opening for the chamber B².

Into the open end of the chamber B³ a plug F' is screwed, which passes through a compressed-air chamber L, said plug having ducts F², which conduct the compressed air from the compressed-air chamber L into the chamber B³, and which ducts can be closed by a valve F³, fixed on one end of a stem F⁴, passing loosely through the plug F' and having its opposite end secured to a diaphragm F⁵, which is held in the outer open end of the plug F' by a cap F⁶, connected with tubes F⁷.

As shown in Fig. 5, the tracker-board or note-sheet bridge E, over which a perforated note-sheet is moved by suitable mechanism, is provided with a chamber E', with which the several ducts E² are in communication by means of short ducts E⁶, adjustable by means of screws E⁷, and these ducts E² are connected with the several tubes D, Fig. 2. By means of tubes E⁸ the air is constantly exhausted from the chamber E', as will be more fully described hereinafter. As long as a duct E² is closed by a solid or closed portion of the note-sheet the air is constantly drawn from this duct and its tube D into the chamber E', and this suction is sufficient to permit atmospheric pressure on the opposite side of the diaphragm C³ to overcome the spring C⁶, Fig. 2, and to hold the valve C² on its seat, thus closing the communication between the chamber B³ and the cap A⁴. The spring C⁶ must of course be gaged and set according to the suction in the chamber E', &c.

As soon as a duct E² is opened to the atmosphere by the registering of a hole in the note-sheet with the end of the said duct in the tracker-board or bridge the suction in the corresponding tube D ceases as the suction in the chamber E' draws in air through the now open duct E². The spring C⁶ now expands and forces the valve-stem C to the right, whereby the valve C' is seated and the valve C² unseated, and thereby the communication between the outer air and the cap A⁴ by means of the vent C⁸, bore B', and

duct B^4 is interrupted, and communication between the cap A^4 and the chamber B^3 is established.

The compressed air from the chamber L acting on the valve F^3 presses the same from its seat and passes into the chamber B^3 and through the bore B' and duct B^4 into the cap A^4 , and acting on the diaphragm A^3 forces the same and the rod A outward. As soon as the duct E^2 in the tracker-board or bridge E is again closed by the note-sheet the suction in the tube D permits atmospheric pressure on the opposite side of the diaphragm C^3 to overcome the spring C^6 , the valve C^2 is seated, the valve C' unseated, and the spring A^6 forces the diaphragm A^3 and rod A inward, the air from the cap A^4 escaping through the vent C^8 . The valve F^3 is seated, as the compressed air cannot escape from the space B^3 and by means of a duct Y can pass to left-hand side of the diaphragm F^3 and press the same to the right. The above operation is repeated every time a hole in the note-sheet a registers with a duct E^2 .

In Fig. 2 I have shown the rod A provided with a head A^7 for striking a key below it; but the rod A can be used for actuating other parts as well. The compressed air, derived from any source whatever, is conducted into the compressed-air tube G , provided with a controlling-valve G' of a suitable construction to be operated pneumatically and the construction of which forms no part of the present invention.

The compressed air after passing the valve G' passes into a valve-casing H , having a compressed-air-inlet neck H' leading to a chamber H^2 in a hub projecting downward from a partition H^1 in the casing H and open at its lower end. This open lower end can be closed by a valve H^5 , attached to a stem H^6 , mounted to slide longitudinally in the hub H^3 , and attached at its upper end to a diaphragm H^7 , held on the casing H by a cap H^8 . A duct H^9 in the partition H^1 establishes communication between the neck H' and the space H^{10} below the diaphragm H^7 . Ducts H^{11} and H^{12} establish communication between the space H^{10} below and the space H^{13} above the diaphragm H^7 .

The casing H has a bottom opening I , which can be closed by the under side of the valve H^5 .

A valve I' is secured on the lower end of a stem I^2 , guided loosely in a bore in a neck I^3 in the cap H^8 and attached at its upper end to a diaphragm I^4 , held in a cup I^5 , attached to the neck I^3 , and having vent-opening I^6 . The diaphragm I^4 is held in place by a cap I^7 , screwed in the cup I^5 and provided with a neck I^8 , from which a tube I^9 extends to a suction-tube J , from which the air is drawn in a manner that will be described hereinafter.

The compressed-air-outlet neck I^{10} of the casing H communicates with the bottom of the casing H .

A spring K is interposed between the diaphragm I^4 and the cap I^7 and has the tendency to press the diaphragm I^4 and valve I' down-

ward. As long as there is suction in the tube J and tube I^9 the atmospheric pressure on the under side of the diaphragm I^4 overcomes the power of the spring K , which is gaged accordingly, and thus the valve I' is held raised and closes the lower end of the bore in the neck I^3 .

The pressure of air is the same on both faces of the diaphragm H^7 , and the compressed air can force down the valve H^5 , close the hole I , and pass out through the outlet-neck I^{10} and tube G^2 to the several compressed-air chambers of the attachment. As soon as the suction is cut off from the tube J in any manner whatever the spring K forces the diaphragm I^4 and valve I' downward, and the latter opens the lower end of the bore in the neck I^3 , thus permitting the compressed air to escape from above the diaphragm H^7 through the bore in the neck I^3 and the vent-opening I^6 . The upward pressure of compressed air on the diaphragm H^7 now holds the valve H^5 against the open end of the hub H^3 , and the flow of compressed air to the compressed-air chambers is interrupted and the compressed air in the same can escape through the hole I in the casing H , which hole is now open. Compressed air passes from the tube G^2 through the tubes G^3 , G^4 , G^5 , and G^6 into the compressed-air chambers L^3 , L^4 , L^5 , and L^6 , respectively, and through a branch tube into the compressed-air chamber for accentuating controllers F , which form no part of the present invention. The several pneumatic mechanisms, like the one shown in Fig. 2, are connected with said compressed-air chambers.

The pneumatic mechanisms not used for striking keys are and need not be provided with the diaphragm F^3 and cap F^6 and are not connected with the tubes F^7 , which lead to the accentuation-controllers F , forming no part of the present invention, Fig. 1.

A vacuum or rarefied-air chamber M is connected with a tube N for exhausting the air from said chamber by any suitable means—such as a suction-pump, bellows, and the like—and from the suction-chamber M a tube N' extends to the pneumatically-controlled suction-valve N^2 , of any suitable construction and the construction and operation of which form no part of the present invention. A suction-tube J is connected with the valve N^2 and is connected by the tubes N^4 , N^5 , N^6 with suction-chambers M^4 , M^5 , M^6 . The suction-tube N' is connected in advance of the controlling-valve N^2 by the tube N^7 with the small suction-chamber M^7 . The suction-tube J is connected by the three-way cock O , having the handle O' , with the tubes E^3 , and said three-way cock O is connected by the tube G^7 with the tube G in advance of the controlling-valve G' . The ends of the note-sheet are secured to two rollers O^2 , O^3 , which are rotated from a compressed-air or other motor O^4 by means of suitable gearing O^5 , having a reversing-gear O^6 , the construction of which rollers, gear, and reversing-gear forms no part of the present invention. The motor O^4

derives its compressed air from the tube G^2 beyond the controlling-valve in the valve-casing H through a tube O^7 , having a cock or valve O^8 . The reversing-gear O^6 is operated by a rod P , pivoted to an arm P' of a rock-bar P^2 , mounted on a standard P^3 , the upper end of which is formed as a valve-casing P^4 , in which the valve-plug P^5 is mounted to turn axially, which plug forms the pivot for the rock-bar P^2 , having an extension P^6 to permit of operating it by hand, Figs. 1 and 4.

Two pneumatic mechanisms Q and R , similar to the one shown in Fig. 2, but reversed, serve for lifting or forcing up either end of the rock-bar. A tube D' extends from the cap C^4 of the pneumatic mechanism Q to the tubular bearing h of the roller O^2 , from which the note-sheet is rolled while playing, and a tube D^2 extends from the cap C^4 of the pneumatic mechanism R to tubular bearing h' of the roller O^3 , upon which the note-sheet is rolled while playing, both rollers having a duct h^3 extending from the bearing h or h' to the surface of the roller, about midway of the length of the same, the end of the duct in either roller being uncovered and opened when the note-sheet is unrolled from the roller. The tubes D' and D^2 are connected by the branch tubes $d^1 d^2$, provided with the regulating-cocks $d^3 d^4$, with the suction-chamber M^7 . The tube S , having a cock S' , extends from the compressed-air-controlling valve G' to the valve-casing P^4 , and the tube T extends from said casing to the valve N^2 in the suction-pipe N' . Ducts T' in the plug P^5 can register with the tubes S and T and connect them with short tubes T^8 open to the air.

U is a pneumatic mechanism for operating a pedal, and U' is a tube extending from the valve mechanism of this pneumatic to the tracker-board or bridge E .

W is a compressed-air tube extending from the compressed-air tube G to the small compressed-air chamber L^8 , Figs. 1 and 4.

The operation is as follows: The three-way cock O is ordinarily adjusted so as to connect the tubes E^3 with the suction-tube J . When the attachment is not operating, the cock O^8 is closed and the cock S' so adjusted as to keep open the tube S . As long as the cock S' is thus set the valve G' closes the tube G , and no compressed air can pass to the several compressed-air chambers. The right-hand end of the lever P^2 is raised, and both tubes S and T are open to the atmosphere at the valve-plug P^5 , and the valve G' is closed, whereas the valve N^2 is open. As long as the valve G' is closed no compressed air can pass to the pneumatic mechanisms, and consequently the attachment cannot play. To play, the cock O^8 is open and the cock S' is shifted to close the tube S at said cock, and in consequence the valve G' is opened, as its construction, which forms no part of the present invention, is such as to open as soon as the tube S is closed. As soon as the valve G' is

opened compressed air can pass to the motor O^4 and operate the same, causing the note-sheet to be unrolled from the roller O^2 and 70 upon the roller O^3 . As the suction apparatus is being worked and as the valve N^2 is open, there is suction in all the suction-chambers, and in consequence thereof the valve I' is held in raised position and the valve H^5 is 75 lowered, permitting the compressed air to pass to the various mechanisms, as the valve H^5 when lowered closes the hole I . As the note-sheet passes over the tracker-board the several pneumatic mechanisms are operated in 80 proper order until the end of the tune is reached, and thereby the duct h^3 in the roller O^2 exposed to the atmosphere. The atmospheric air passes through the tube D' to the valve mechanism of the pneumatic mechanism Q , which is thus operated, and thereby the left-hand end of the lever P^2 is thrown up and the winding-gear reversed, so as to reroll the tune-sheet from the roller O^3 upon the roller O^2 . At the same time the tubes S and 90 T are closed at the plug P^5 , the former, however, without effect, as the tube S has already been closed by the cock S' ; but by the closing of the tube T the main suction-valve N^2 is closed, thus causing the valve I' to be lowered and the valve H^5 to be raised, thus cutting off compressed air from all the compressed-air chambers. The construction of this valve, which forms no part of the present invention, is such as to close when the 100 tube T is closed. When the tune-sheet is rerolled upon the roller O^2 , the duct h^3 in the roller O^3 becomes exposed and atmospheric air can pass to the valve mechanisms of the pneumatic mechanism R and the right-hand end of the lever P^2 is thrown upward. Thereby the driving-gear is reversed again, and the roller O^3 is thrown in gear and the note-sheet again rolled upon the roller O^2 . At the same time the tubes S and T are opened 110 at the plug P^5 , the former again without effect, as the tube S remains closed at the cock S' . By the opening of the tube T at the plug P^5 the valve N^2 is opened, and thus all suction-chambers again brought in communication with the main suction-chamber, and so 115 on, the tune-sheet being rolled alternately from one roller upon the other until the cock S' is opened. If the cock S' is opened while the instrument is playing, it stops at once, as 120 thereby the valve G' is closed at once, and thus all compressed air shut off; but if the cock S' is opened during rerolling of the tune-sheet upon the roller O^2 the compressed air is not shut off until the sheet has been entirely 125 rerolled, as the opening of the cock S' has no effect because the tube S is closed at the plug P^5 . When the sheet is rerolled, the lever P^2 is thrown up at the right-hand end, and thereby the tube S is opened at the plug P^5 , and as 130 it has already been opened at the cock S' the valve G' is closed instantly and the entire mechanism stopped.

If at any time when a note-sheet is partly

unrolled from the roller O² it is desired to re-roll the same, it is only necessary to depress the right-hand end P⁶ of the rock bar or lever P², and this has the same effect on all parts 5 as the automatic lowering of this lever at the end of a tune.

Some of the lint from the note-sheet is drawn 10 into the air-passages, and when it is desired to clean them the three-way cock O is so adjusted as to connect the tubes E³ with the compressed-air tube G. The compressed air then forces the lint, dust, &c., out of the tubes E³ and air-passages connected therewith.

Having described my invention, what I desire 15 to secure by Letters Patent is—

1. In a playing attachment for musical instruments, a pneumatic mechanism composed of a casing, a rod in the same, means in the casing for moving the rod lengthwise by compressed air, a valve for admitting compressed air into said casing, a spring acting on said valve to unseat the same and means for counteracting said spring by suction, and means for automatically destroying said suction, at 20 times, substantially as herein shown and described.

2. In a playing attachment for musical instruments, a pneumatic mechanism composed of a casing, means in the same for moving a rod lengthwise by compressed air, a rod in said casing, a valve for admitting compressed air into said casing, a spring acting on said valve to unseat the same and means for counteracting said spring by suction, substantially 25 as herein shown and described.

3. In a playing attachment for musical instruments, a pneumatic mechanism composed of a casing, means in the same for moving a rod lengthwise by compressed air, a rod in said 30 casing, a valve for admitting compressed air into said casing, a spring acting on said valve to unseat it and a diaphragm and suction-tube for counteracting said spring, substantially as herein shown and described.

4. In a playing attachment for musical instruments a pneumatic mechanism composed of a casing, means in the same for moving a rod lengthwise by compressed air, a rod in said 40 casing, a valve for admitting compressed air into said casing, a suction device for seating

the valve, and a spring for unseating the valve, substantially as herein shown and described.

5. In a playing attachment for musical instruments a pneumatic mechanism composed of a chamber, a suction-duct connected with said chamber, a diaphragm in the chamber, a valve-stem impinging on said diaphragm and a spring for moving the diaphragm adversely to the spring, substantially as herein shown 55 and described.

6. In a playing attachment for musical instruments a pneumatic mechanism composed of a chamber, a suction-duct connected with said chamber, a diaphragm in the chamber, 65 means for admitting atmospheric air to one face of the diaphragm, a spring for pressing said diaphragm adversely to the pressure of the atmospheric air and a valve-stem impinging against the diaphragm, substantially as 70 herein shown and described.

7. In an automatic playing attachment for musical instruments, the combination with a series of pneumatic mechanisms to be operated by compressed air, of valves for the same, 75 means for controlling said mechanisms by suction, a compressed-air-supply tube, a valve-casing in said tube, a valve in said casing and means for controlling said valve by suction, substantially as herein shown and described. 80

8. In an automatic playing attachment for musical instruments the combination with a series of pneumatic mechanisms to be operated by compressed air, of valves for the same, means for controlling said mechanisms by suc- 85 tion, a compressed-air-supply tube, a valve-casing in said tube, a valve in said casing and means for controlling said valve by suction, a suction-tube, a valve-casing in the suction-tube, a valve in the same, and a tube extending 90 from the valve-casing in the compressed-air tube to the suction-tube, substantially as herein shown and described.

Signed at New York city, in the county of New York and State of New York, this 6th 95 day of May, A. D. 1901.

HARRY M. SALYER.
